(57) **CLAIM**

The ornamental design for a garment, as shown and described.

DESCRIPTION

FIG. 1 is a front view of a first embodiment of a garment illustrating the new design;

FIG. 2 is a rear view thereof;

FIG. 3 is a left side view thereof;

FIG. 4 is a right side view thereof;

FIG. 5 is a front view of a second embodiment of a garment illustrating the new design;

FIG. 6 is a rear view thereof;

FIG. 7 is a left side view thereof; and,

FIG. 8 is a right side view thereof.

The broken line portions form no part of the claimed design. The dash-dot-dash boundary lines shown in the drawings define the bounds of the claimed design and form no part thereof.
